(57) CLAIM

The ornamental design for a cosmetic dispenser case, as shown and described.

DESCRIPTION

FIG. 1 is a front perspective view of a cosmetic dispenser case with a lid, caps, a latch, a latch capture, wells, and a hinge shown in broken lines for context;

FIG. 2 is a top plan view of an interior of a base of the cosmetic dispenser case of FIG. 1, with the lid, the caps, the latch, and the wells shown in broken lines for context;

FIG. 3 is a side elevation view of the cosmetic dispenser case of FIG. 1, with the lid, the caps, the hinge, and the latch shown in broken lines for context;

FIG. 4 is a top plan view of the cosmetic dispenser case of FIG. 1, with the lid and the latch shown in broken lines for context;

FIG. 5 is a front elevation view of the cosmetic dispenser case of FIG. 1, with the lid and the latch shown in broken lines for context;

FIG. 6 is a back elevation view of the cosmetic dispenser case of FIG. 1, with the lid shown in broken lines for context; and,

FIG. 7 is a side elevation view of the cosmetic dispenser case of FIG. 1, with the lid and the latch shown in broken lines for context.

The broken lines are directed to environment and are for illustrative purposes only.

The broken lines form no part of the claimed design.
